(57) **CLAIM**

The ornamental design for a contoured pillow, as shown and described.

DESCRIPTION

FIG. 1 is a front perspective view of a contoured pillow, showing my new design;

FIG. 2 is a front view of thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The solid line showing of a plurality of the letter "Z" in FIGS. 1 through 6 indicates a surface pattern of the claimed design.
